UNITED STATES PATENT OFFICE.

JOHN W. ANDERSON, OF LANCASTER, PENNSYLVANIA, ASSIGNOR TO ADAM B. GROFF, OF SAME PLACE.

VEGETABLE-SLICING MACHINE.

SPECIFICATION forming part of Letters Patent No. 252,595, dated January 24, 1882.

Application filed November 25, 1881. (No model.)

To all whom it may concern:

Be it known that I, JOHN W. ANDERSON, a citizen of the United States, residing at Lancaster, in the county of Lancaster and State 5 of Pennsylvania, have invented new and useful Improvements in Slicing Machines, certain parts of which improvements are specially applicable to the slicing-machine of myself and Adam B. Groff, patented November 1, 1881, and 10 numbered 249,139; but the principal novel part is applicable to other slicers as well, as will appear in detail in the following specification.

My invention comprises the following novel and useful features: A downward-folding 15 presser or feeder and knife-guard, hinged horizontally at the top of the machine-frame, and operating to press the articles to be sliced up to the knife without endangering the hand of the operator, the said part having on its advanced side projections, ridges, or teeth with which to take hold on articles to be sliced in such manner as to prevent their being rolled while the knife is being drawn back, and said part may also be laid back, out of the way, on 20 top of the frame when large articles are being sliced until they are reduced, when it may be returned to complete the slicing of the article, which may thus be totally sliced, certain stops arresting the presser at the end of the operation. The presser and guard is so arranged 25 as to press most easily, to be quickly dispensable, and to be entirely unobstructive. All these advantages over other pressers are obtained by hinging it horizontally at the top of the slide-frame.

In the accompanying drawings, Figure 1 represents a perspective front view of my invention with the presser folded. Fig. 2 is a cross-section of the same, taken at the indicated line 40 α , Fig. 1, the presser being shown thrown back, but indicated in position at work. Fig. 3 represents a rear side view of my slicer. Fig. 4 is a perspective view of the presser. Fig. 5 is an edge view of one of my adjustable gage-attaching fixtures.

In the following description, referring to the drawings, similar letters refer to similar parts throughout all the views.

A denotes the presser or guard. k is a knob

thereon for handling it. $p p$ are projections 50 thereon for seizing articles. ff are pins thereon for stops in notches $e e$.

$h h$ are extensions on cross-frames C D, to which the presser is hinged in position, as shown.

Z represents an article to be sliced. It lies on the table E, and between the presser A and the gage B'.

S denotes the head-board; m, a plate on its front edge, provided with pin o, which holds 60 in plate n, which latter is attached to table E and sill V, as shown in Figs. 1 and 2.

T denotes a pin in heel of head board S, which sets in hole in table E.

d is a binding-screw supported in arm l on 65 frame C. Said screw sets at its shouldered point in a properly brushed hole on the edge of said board S. Said screw and pins firmly sustain said board and table in position when the screw is taut. When the latter is withdrawn 70 said parts may be folded.

G G' denote chairs on back of the gage B' and on the ledges B B'.

P denotes a folding arm having its ends pivoted to-said chair-extensions, as shown in Fig. 5. 75

N denotes the gage-locking arm; L, its post, to which it is held by binding-screw g.

For securing by Letters Patent of the United States the new and useful features of my invention, I claim—

The folding presser and guard A, hinged horizontally to extensions $h h$, or their equivalents, on the frame C, provided with projections $p p$ on its face, and stops ff on its lower margin, registering with the notches $e e$ in the top of 85 table E, and operating both to press an article, Z, between it and the gage B' before the knife K, and adapted to be laid back out of the way on the top of frame C in the manner and for the purpose set forth.

In testimony that I claim the foregoing as my invention I have hereunto set my hand and seal this 18th day of November, 1881.

JOHN WESLEY ANDERSON. [L. s.]

Attest:

J. K. BARR,
THOS. F. M. ELLIGOTT.
